WOOD WOOL COVERING

Heinrich Schneider and Karl Schneider, Kahl-on-the-Main, Germany, assignors to E. Merek, Darmstadt, Germany, a firm of Germany

Application August 2, 1928, Serial No. 297,036,
and in Germany August 10, 1927

3 Claims. (Cl. 154—54)

Wood wool and other loose short-filamentous materials have been used for packing for a long time as well as wood, straw and other long-filamentous materials. Up to now solid coverings 5 were made only of straw and the like long-filamentous materials, but not of short-filamentous materials. They were made e. g. by winding them up on round cylinders, sewing them up whilst another cylinder-like vessel surrounded the first 10 mentioned cylinder parallel to it.

The object of the present invention is a process and a device for the manufacture of coverings or wrappers of any short-filamentous, loose material, especially of wood wool. Furthermore the 15 present invention shows an apparatus especially adapted for carrying out the process of the present invention. According to the invention a rotating metallic winding case is used to wind up the wood wool, the aforesaid metallic winding 20 case being enclosed in another one that is fixed. The shape of the two cases is a round preferably circular one. The material to be used e. g. wood wool may be introduced between the two cases in any suitable manner. The best way to supply 25 the material is by means of slits being provided in the exterior case. The raw material is introduced through these slits while the interior metal case is rotating and is wrapped up round the said interior case in the shape of the latter. Further- 30 more it is of advantage to provide on the interior metal case means to pull up the raw material, preferably detachable catch pins.

Finally it has been established that the use of any of the well-known methods of sewing bottle- 35 coverings advantageously may be used in connection with the present invention. The most practical way for this purpose is to provide the interior case with several longitudinal or cross slits, through which the chips or threads of the wood 40 wool on the case can be sewed up with each other. In the subjoined drawing the invention is represented by way of example.

Fig. 1 shows a longitudinal section of the new device,

Fig. 2 a cross section of the same.

A case (1) that may have a cylindrical cross section is fitted on a winding frame with an ordinary spindle and a sliding rod, which frame is not represented in the drawing. The said metal 50 case is turning in bearings (2), which are connected with the exterior case (3). This outer case (3) is fixed, so that the interior case (1) is revolving inside the same, viz at a rate of about 55 to 60 rotations a minute. The outer metal case (3) is fixed to a slit (4) at a stationary slit

connection. The interior case (1) has three longitudinal slits (5) in the form of embodiment given in Fig. 2 of the drawing. The exterior metal case (3) has likewise three longitudinal slits (6) lying above the longitudinal slits (5). Of 60 these exterior slits, the upper one, through which the wood wool is fed by hand, is larger. Inside the interior case (1) a ledge (7) is arranged, to which are fitted catch pins (8) that pass through the wall of the interior case (1) in the respective 65 holes.

The ledge (7) is pressed by a spring (9) against the inner wall of the metal case (1), while it can be drawn out of the said metal case (1) by means of rings (10) placed at its ends, after the 70 catch pins have been lifted out of the holes of the metal case (1) counter to the pressure of the spring (9). As soon as the required strength of the protective covering to be manufactured has been obtained by the repeated rotation of the 75 interior case, both the metal cases are placed above a sewing machine, where the covering arranged between the two metal cases is sewed in such a manner that the sewing-needle, together with the seam, will lie at the slits (5 and 6). 80 The outer metal case is only removed after the wood wool has been sewed up, whereupon the finished covering is removed from the inner case. The case may be of any suitable material advantageously of metal.

By the process explained above and the devices described a protective covering, especially of wood wool, is produced that may be applied to various purposes. It will prove particularly 90 advantageous and practical when forwarding by mail glasses or bottles filled with chemical liquids in consignments or shipments with which the use of straw, cardboard, pasteboard and the like is prohibited by law in conformity with home or foreign regulations. The novel covering can be given any form, according to the object which it has to cover or protect. It may be manufactured in a cylindrical, conical, oval or bottle-like shape, and will adopt any other form 95 which the metal case must have in accordance with the object in question.

We claim:

1. As a new article of manufacture, a protective covering consisting of loose, short intertangled filaments compactly arranged and 105 matted together to form a web and a row of binding stitches extending across said intertangled filaments and said web and holding the filaments in place.

2. As a new article of manufacture, a protect- 110

ing covering comprising a web formed of wood wool, the filaments of which are short, intertangled and matted together and a line of stitches extending across said intertwined and matted filaments and said web and binding the wood filaments together at its point of intersection therewith.

3. A covering as claimed in claim 2, in which

the web is endless so that it forms a continuous fabric which may be opened to receive an article to be covered and protected thereby and in which there are a plurality of the binding lines of stitches spaced apart.
